UNITED STATES PATENT OFFICE.

JOSEPH REYNOLDS, OF PROVIDENCE, RHODE ISLAND.

MARINE PROPULSION.

Specification of Letters Patent No. 27,156, dated February 14, 1860.

To all whom it may concern:

Be it known that I, JOSEPH REYNOLDS, of Providence, in the county of Providence and State of Rhode Island, have invented 5 certain Improvements in Propelling Boats or Vessels, and that the following is a full, clear, and exact description thereof, reference being had to the accompanying drawings, making a part of this specification, in 10 which—

Figure 1, is a plan. Fig. 2, is a side view, representing four propellers, two at each side of the boat, no portion of the boat being shown. Fig. 3, is an end view, as from the 15 stern of boat, showing one of the main shafts with a propeller hung to each crank pin. Fig. 4, represents the back side of the lower portion of one of the propellers, between the crank arms, showing the side 20 pieces and rib piece as connected to the float, the stay rods being removed, also showing the cross pieces, or braces which probably will not be required when the float is permanently secured to the frame.

25 The term backside in reference to Fig. 4, means that side toward the forward part of the boat or vessel.

My improvements in propelling vessels, consists in constructing and operating the 30 propelling apparatus as follows: One or more main shafts are placed across the vessel, being connected together, and to which the power is communicated by connecting rods, or gearing. At each end of the shafts 35 on the outside of the hull of the vessel is attached a crank arm, each of these arms are connected by a crank pin, to other arms of the same length, attached to short shafts or journals, placed in a right line with the 40 main shafts and supported in journal boxes by pedestals attached to the guards of the boat or vessel, thus forming a double crank, possessing an equal amount of strength as the straight shaft of the paddle wheel. The 45 width between the crank arms, or the length of the crank pin that connects the arms, must be in the clear sufficient for the length of float required to propel the vessel. These 50 double cranks, which are the propeller cranks, may be constructed by having disks in the place of the crank arms, connected

by a crank pin in the same manner as the arms are connected. The disks may be constructed to act as a counter balance to the crank by having the greatest weight opposite to the crank pin. On each crank pin is hung a propeller or propeller frame, at the lower end of which the float or bucket is attached, the top being supported and guided by radius rods or some other suitable mode.

55 The propeller frames are constructed as follows: by having two upright side pieces to each frame, either of wood, metal, or other suitable substance, framed, bolted, or riveted to cross pieces of a proper length, to give 60 the frame a suitable width, for strength, and support of the float. In case the width of the frame is so great as to require other supports for the float besides the two side pieces, and to give further strength to the frame, 65 one or more upright pieces or ribs may be connected to the frame between the two side pieces, and secured to the cross pieces in a proper manner. The drawing hereunto annexed represents a frame constructed with 70 one rib piece in the center secured in with the cross pieces, the said cross pieces being placed diagonally with the frame for the purpose of acting as braces, at the same time supporting and keeping the frame to its 75 proper width. Other cross pieces placed horizontally across the frame may be applied if required. That way of the frame to which the greatest strain occurs by the propelling action is supported and made sufficiently strong by having stay rods on one 80 or both sides of the side pieces, and on the rib pieces if required, and secured at or near both top and bottom of the frame. The top 85 ends of the stay rods are fitted with screws for the purpose of tightening the same when required. These stay rods are braced out at or near that part of the frame where the crank pin is connected to a proper distance 90 to give strength to the frame, by having 95 projecting rests, or bearings over which the stay rods are drawn, and by which they are kept braced out. These projecting rests or bearings will be placed and secured to the side pieces and ribs, at or near that part of 100 the frame before named, where the crank pin connects, and such other places in the

length of the frame as may be found necessary, or best, and will be secured by cross pieces or braces if required to keep them in a proper position.

5 The propeller frames may be of equal width at both top and bottom, or they may be somewhat contracted at the top, but should be a suitable width to be supported and guided by two radius rods or two sets of fixed guides. I think radius rods are preferable to fixed guides for supporting and guiding the tops of the propeller frames, and that two to each frame will be better than one for the purpose of keeping the frame steady and making it more secure, unless for small vessels or boats where a narrow frame is sufficient. If guided and supported by fixed guides, adjustable cross-heads may be placed across the tops of the frames, projecting over the side pieces, and fitted in a proper manner to be guided by the fixed guides at each side of the frame, or adjustable boxes or pieces to fit in or on the fixed guides, may be attached to the tops of the frames, in such manner as that they will adjust themselves in the guides as the frame changes its position.

10 The fixed guides may be formed either with a curve or straight, and placed in such a position and at such an angle with a vertical line as will give to the float an increase in its speed while in the act of propelling the boat or vessel forward, similar to what will be produced when supported and guided by radius rods, as will be hereafter described. The float or bucket which is attached to the lower end of the propeller frame may be either flat, concave, or any other suitable form, and will be set at such 15 an angle with the propeller frame, or a line from the center of the crank pin to the center of the guiding point or hanging of the radius rods at the top of the frame, as will give it a proper position to enter and leave the water in the best manner. The float may either be bolted fast to the frame or hung with journals or hinges in such a manner as that with a simple arrangement of machinery it will be locked and made fast to the frame while in the act of propelling the vessel either way, and will be unlocked and free to yield if it comes in contact with the water when returning to take a new hold to propel the vessel forward. The propelling cranks may be so arranged on the shaft as 20 partially to equalize the application of the power to the load or resistance of the float in the water when in the act of propelling the boat forward.

25 An important point in the operation is a uniform action and increase in the speed of the floats while in the act of propelling the vessel forward, caused by having the top of each frame supported and guided by radius rods hung to the vessel or suitable frames at-

tached to the vessel abaft the main shaft to 70 which the propeller frame is connected. The radius rods to be of a suitable length and hung in a proper position to hold or 75 guide the top of the frame forward or beyond the shaft to which it is attached as will be more fully shown by reference to the drawings hereunto annexed. To give a similar action or increase in the speed of the float when guided by fixed guides to that 80 produced by being guided by radius rods as before described, the fixed guides will be formed with a curve or straight and set at a proper angle with a vertical line so as to cause the top of the frame to incline or move toward the stern of the vessel while in the 85 first part of its action to propel the vessel forward, and to incline or move the other way or toward the forward part of the vessel in the latter part of its forward propelling action. If the fixed guides are placed 90 in front of a vertical line with the shaft to which the frame is connected, the curve or angle will require to be less than if placed directly over or abaft of it.

a a, are the main shafts supported in journal boxes and pedestals in the usual way. 95

b b, are the crank arms secured to the main shafts.

c c, are the crank arms secured to the short shafts or journals d d, the two arms being 100 connected together by the crank pin e.

f f, are the pedestals connected to the guards of the vessel.

g g, are the side pieces of the propeller frame, h the rib piece, k k, the cross pieces.

l l, are the stay rods, braced out and supported by the projecting rests or bearings m m.

n is the float or bucket.

o is the cross shaft at the top of the propeller frame, to which one end of the radius rods p p, are connected, the other ends being connected to the shaft q attached to the vessel.

Having thus fully described the nature 115 of my invention, and the manner in which the same is constructed and acts, I wish to be understood as not claiming the parts disconnected from each other, or aside from combination or application to the particular mode of propulsion herein described. Neither 120 do I claim a propeller apparently similar in its operation to the one herein described, having only a single stem at the top, and guided by a single radius rod, or a single set of guides in or about the stem, unless embracing, or in combination with some of the essential points herein described and hereafter claimed. But

What I do claim is—

The double cranks supported by outside 130 bearings, with the propeller frames supported by stay rods, and guided, at the top, with two radius rods to each frame, hung to the

vessel or suitable frames attached to the vessel abaft the main shaft to which the propeller frame is connected. The radius rods to be of a suitable length and hung in a proper position to hold or guide the top of the frame forward or beyond the shaft to which it is attached. The whole constructed and arranged substantially as, and for the purposes specified.

JOSEPH REYNOLDS.
